(57) **CLAIM**

The ornamental design for a rattan iron bed, as shown and described.

DESCRIPTION

FIG. 1 is a top, front perspective view of a rattan iron bed, showing my new design;

FIG. 2 is a bottom, rear perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 a partial enlarged view of portion 9 in FIG. 1;

FIG. 10 a partial enlarged view of portion 10 in FIG. 1;

FIG. 11 a partial enlarged view of portion 11 in FIG. 2; and,

FIG. 12 a partial enlarged view of portion 12 in FIG. 2.

The broken lines in the figures illustrate portions that form no part of the claimed design.
